UNITED STATES PATENT OFFICE.

ROBERT W. CARTER, OF LOS ANGELES, CALIFORNIA.

SHEET-METAL-ROLLING MACHINE FOR FENDERS AND THE LIKE.

1,244,422.

Specification of Letters Patent.

Patented Oct. 23, 1917.

Application filed May 23, 1917. Serial No. 170,424.

To all whom it may concern:

Be it known that I, ROBERT W. CARTER, a citizen of the United States, residing at Los Angeles, in the county of Los Angeles 5 and State of California, have invented new and useful Improvements in Sheet-Metal-Rolling Machines for Fenders and the like, of which the following is a specification.

This invention relates to a metal working machine and particularly pertains to a machine for forming automobile fenders and other sheet metal objects.

It has been common practice in the automobile industry to form the fenders and other sheet metal parts of the body by the use of forming dies which act under pressure to press the parts into the shape desired. This method of operation has proven very expensive, due to the fact that 20 the dies are intricate and also for the reason that considerable time is consumed in pressing them. It is the principal object of this invention to provide a machine for forming sheet metal parts which does not 25 require large and cumbersome forming dies, but which permits the parts to be rolled into shape in a rapid and simple manner.

Another object of this invention is to provide an apparatus by which duplicate parts 30 may be readily formed when the originals have been produced by dies which are not accessible. In the present method of duplicating parts, such as fenders, the sheet metal is formed by peening, which process is 35 long and tiresome. In the use of the present machine the same parts may be accurately formed and turned out in a workman-like manner with great rapidity.

Another object of this invention is to provide 40 a machine of the above class which is comparatively simple in its construction and very inexpensive in its initial cost, in comparison with other machines used for a similar purpose.

Another object of this invention is to provide 45 a metal working machine which may be easily adjusted and fitted for producing a wide range of objects.

It is a further object of this invention to provide 50 a machine which is not subjected to violent strains, possesses few parts, all of which are strong and durable.

Other objects will appear hereinafter.

The invention is illustrated, by way of ex-

ample, in the accompanying drawings in 55 which:

Figure 1 is a view in side elevation illustrating the complete metal working machine as equipped to form an automobile fender.

Fig. 2 is an enlarged view in section and 60 elevation as seen on the line 2—2 of Fig. 1 particularly disclosing the formation of the movable forming member and the templet over which it is adapted to be moved.

Fig. 3 is a view in plan illustrating the 65 templet.

Fig. 4 is a view in transverse section as seen on the line 4—4 of Fig. 2 illustrating the manner in which the roller weights are positioned upon their hangers. 70

Referring more particularly to the drawings, 10 indicates a frame composed of vertically extending posts 11 and 12 and connecting timbers 13 and 14. The timber 14 is adapted to rest upon the ground. Secured 75 to this timber and extending upwardly therefrom is a templet base 15. In the present instance this base is shown as having a semi-circular seat 16 formed across its upper face. This semi-circular portion is 80 covered with a sheet of metal 17 upon which the mold, or templet 18 is adapted to rest. The templet has an arcuate outer face which is described by the same circle as that of the arcuate face 16 of the base. In this manner the templet may be slid back and forth in the direction of the arrow —a—. The upper face of the templet 18 is here shown as arcuate in its longitudinal contour. It will be understood that this face corresponds 85 with the outer surface of the article to be formed. In the present instance the article is a fender, as indicated by the dotted lines 90 in Fig. 1.

Pivots secured to the upper cross-beam 95 13 by means of a pivot bolt 20 are shackle links 21. The lower ends of these links are fitted with a lever pivot pin 22 by which a vertically swinging lever arm 23 is pivotally supported. The outer end of this arm 100 is adjustably supported by a chain 24 which is wrapped around a tackle block 25. This block is of common construction, being fitted with a differential clutch adapted to be actuated by an operating chain 26 to 105 lengthen and shorten the downwardly hanging chain 24 and thereby vertically adjusting the lever 23. The radius arm 27 is piv-

totally secured to the lever arm 23 near its center by a pin 28 which permits it to hang vertically. The pin 28 supports the radius arm in substantially vertical alinement with the center of the base 15.

The radius arm is provided as a swinging support for a forming member 29. This member is here shown as a roller, circular in transverse section and oval in longitudinal section. It will be understood, however, that a fixed member having a face of the same contour as the roller might be used, if desired. The arcuate face of the roller is described by a smaller arc than the arc forming the concave face of the work to be formed, as particularly shown in Fig. 2 of the drawings. In this manner the roller may be swung transversely of the templet 18 so that it will be held upon the fender blank by the weights 42. The handle 39 may then be grasped and the roller moved back and forth over the surface of the metal, causing it to become stretched between the side edges and to assume the desired contour in cross-section. After the roller has passed along the central portion of the fender, the lock pin 38 may be removed from the shank 31 to permit it to be set at an angle to the radius arm 27, thus insuring that the blank will be uniformly stretched. It is also evident that the pin may be entirely removed and the roller moved across the blank and back and forth at random. Attention is directed to the fact that the arc of travel of the roller, as described from the pivot pin 28, is greater than the arc describing the longitudinal contour of the fender. This insures that the roller will bear down upon the fender blank. After an area of the fender has been stretched, the templet 18 may be slid back and forth upon the base block 15 in the direction indicated by the arrow —a—. This will permit the entire fender to be formed and caused to permanently assume the desired contour. When the blank has been sufficiently stretched it may be removed by loosening the clamping members 45 and raising the lever arm 23 to relieve the roller 29 from the work. It will be understood that the templet is preferably formed of wood and may be made of two adjustable parts 47 and 48, as shown in Fig. 2, or of one piece 49, as shown in Fig. 3. The parts 47 and 48 are clamped together by clamping bolts 50 which engage clamping arms 51 and 52 fastened at the opposite ends of the templet.

In order that the forming member 29 will bear at all times against the metal sheet 40 with the desired pressure, brackets 41 are secured upon the opposite sides of the radius arm 27 and are adapted to receive a desired number of weights 42. These weights are formed with radial slots 43 which permit them to be easily mounted or removed from the shanks 44 of the brackets 41. In this manner variable pressure may be constantly exerted upon the forming member 29, as determined by the contour of the object formed and the gage of the metal being worked.

The blank 40, from which the object is formed, is held in position upon the face of the templet by means of adjustable clamps 45 which occur at intervals along the sides of the templet and over-hang the upper face of the templet to secure the blank against metal strips 46 fastened along the marginal edges of the templet, as particularly shown in Fig. 2 of the drawings.

In operation, the metal sheet 40 is forced to pass through a set of forming rollers 65 which give it the arcuate longitudinal shape

shown in Fig. 1. These rollers also turn the flange 40' along the sides of the sheet. When this initial operation has been completed, the blank is positioned upon the templet 18 and there secured by the clamps 45. The pulley block 25 is then actuated by the chain 26 to lower the forming roller 29 so that it will be held upon the fender blank by the weights 42. The handle 39 may then be grasped and the roller moved back and forth over the surface of the metal, causing it to become stretched between the side edges and to assume the desired contour in cross-section. After the roller has passed along the central portion of the fender, the lock pin 38 may be removed from the shank 31 to permit it to be set at an angle to the radius arm 27, thus insuring that the blank will be uniformly stretched. It is also evident that the pin may be entirely removed and the roller moved across the blank and back and forth at random. Attention is directed to the fact that the arc of travel of the roller, as described from the pivot pin 28, is greater than the arc describing the longitudinal contour of the fender. This insures that the roller will bear down upon the fender blank. After an area of the fender has been stretched, the templet 18 may be slid back and forth upon the base block 15 in the direction indicated by the arrow —a—. This will permit the entire fender to be formed and caused to permanently assume the desired contour. When the blank has been sufficiently stretched it may be removed by loosening the clamping members 45 and raising the lever arm 23 to relieve the roller 29 from the work. It will be understood that the templet is preferably formed of wood and may be made of two adjustable parts 47 and 48, as shown in Fig. 2, or of one piece 49, as shown in Fig. 3. The parts 47 and 48 are clamped together by clamping bolts 50 which engage clamping arms 51 and 52 fastened at the opposite ends of the templet.

In the modification shown in Fig. 3 the secondary side bar 46' is inserted inside of one of the side strips 46 when it is desired to form a narrow portion of the mud-guard, the bar serving to fit a longitudinally curved edge.

It will thus be seen that the metal working apparatus here disclosed is inexpensive in its construction, decidedly simple in operation, and will readily produce the results desired.

While I have shown the preferred construction of my rolling machine for fenders as now known to me, it will be understood that various changes in the combination, construction and arrangement of parts may be made by those skilled in the art without departing from the spirit of my invention.

I claim:

1. In a sheet metal working machine, a base arcuate longitudinally, an arcuate templet mounted upon the base and adapted for longitudinal movement, means for detachably securing a sheet metal blank upon said templet, a support above the templet, and a forming roller depending from the support and adapted to engage the sheet metal blank and adapted to swing crosswise and longitudinally.

2. A sheet metal working machine, comprising a base, an arcuate seat formed upon said base, a templet adapted to rest within said seat and formed with an arcuate face whereby it may slide along said seat, a super-structure built over said base, a lever arm secured to said super-structure and adapted to be vertically moved, a forming member pivotally supported from said lever arm and adapted to move over the upper surface of the templet, and means whereby pressure may be constantly applied to said forming member.

3. A sheet metal working machine, comprising a base, an arcuate seat formed upon said base, a templet adapted to rest within said seat and formed with an arcuate face whereby it may slide along said seat; a super-structure built over said base, a lever arm secured to said super-structure and adapted to be vertically moved, a forming member pivotally supported from said lever arm and adapted to move over the upper surface of the templet, means whereby pressure may be constantly applied to said forming member, and means whereby the roller pressure may be varied.

4. A sheet metal working machine, comprising a base, an arcuate seat formed upon said base, a templet adapted to rest within said seat and formed with an arcuate face whereby it may slide along said seat, a super-structure built over said base, a lever arm secured to said super-structure and adapted to be vertically moved, a forming member pivotally supported from said lever arm and adapted to move over the upper surface of the templet, means whereby pressure may be constantly applied to said forming member, means whereby the roller pressure may be varied, and means for raising and lowering the forming member in relation to the templet.

5. A sheet metal working machine, comprising a base, an arcuate seat formed upon said base, a templet adapted to rest within said seat and formed with an arcuate face whereby it may slide along said seat, a super-structure built over said base, a lever arm secured to said super-structure and adapted to be vertically moved, a forming member pivotally supported from said lever arm and adapted to move over the upper surface of the templet, means whereby pressure may be constantly applied to said forming member, means whereby the roller pressure may be varied, means for raising and lowering the forming member in relation to the templet, and means for detachably securing a sheet metal blank upon the templet in a position to be acted upon by the roller.

In testimony whereof I have signed my name to this specification.

ROBERT W. CARTER.
